UNITED STATES PATENT OFFICE

2,138,450

RAILWAY PILOT STRUCTURE

Einar G. Hallquist, Wallingford, Pa., assignor to
 General Steel Castings Corporation, Granite
 City, Ill., a corporation of Delaware

Application June 26, 1936, Serial No. 87,486

9 Claims. (Cl. 213—4)

The invention relates to railway locomotive pilot, coupler, coupler counterbalance and uncoupling mechanism and consists in novel construction and assembly of these parts whereby they may be moved into one position for the coupler to function by engaging an adjacent vehicle or into another position in which the coupler is moved out of functioning position and the pilot assumes a form and appearance substantially as though a coupler were not mounted thereon. In such constructions, the pilot is recessed to receive the coupler and reference is made to Patent No. 1,724,194, issued to the present applicant on August 13, 1929 and illustrating an arrangement of this general type.

One object of the present invention is to strengthen a pilot of this "recessed" type whereby in the event of the pilot striking an object on the track there will be less likelihood of the pilot or the coupler structure mounted thereon being injured.

Another object of the invention is to maintain a continuous smooth surface from side to side of the pilot and from top to bottom thereof when the coupler is moved out of functioning position, thereby improving the appearance of the forward end of the locomotive in accordance with more recent designs of locomotive structure in which smooth contours and "streamlining" effects are being sought.

The above mentioned objects are attained by mounting the coupler so that its head swings upwardly and rearwardly from its functioning position and a portion spaced from its head swings forwardly to close the front part of the recess in the pilot through which the coupler shank and head project when in functioning position. This arrangement makes it impossible to utilize the usual uncoupling rod mechanism extending over the top of the coupler, and another object of the present invention is to adapt uncoupling mechanism operated from the side of the pilot in the usual manner so that it will accommodate movement of the coupler head and shank as described above.

These general and other detailed objects of the invention are attained by the illustrative structure shown in the accompanying drawings, in which—

Figure 1 is a side view of the forward end of those parts of a locomotive to which the present invention relates, including the pilot beam, pilot, coupler, and uncoupling mechanism, the coupler head being shown in functioning position.

Figure 2 is a section through the pilot beam

and pilot taken longitudinally of the locomotive but with the coupler device shown in elevation.

Figure 3 is a top view of the structure shown in Figures 1 and 2.

Figure 4 is a horizontal section through the pilot taken substantially on the line 4—4 of Figure 1.

Figure 5 is a partial front elevation of the structure.

Between the forward ends of the locomotive side frames 1 is mounted a front end central member 2 and exteriorly of frames 1 are front end side members 3, members 2 and 3 cooperating to form a pilot beam. A locomotive pilot 4 is bolted to this pilot beam as indicated at 5. Central end member 2 has depending brackets 2a for backing up the pilot, and side members 3 have similar depending brackets 3a. Preferably the pilot mounting provides for vertical adjustment of the pilot towards and from the rail as is well known in the art.

The pilot front wall 7 has an inclined rounded nose or central portion and extends outwardly and rearwardly therefrom to merge at the top and sides in substantially flattened wall sections 8 and 9, respectively. The angular section 10 extends transversely of the structure between the lower rear corners of wall sections 9, and reinforcing ribs 11 brace the structure intermediate its sides. Preferably the pilot is cast in one piece with steps 12 formed integrally thereon and merging with the forward wall. The forward upper central part of the nose portion has a U-shaped recess as indicated at R.

The coupler device includes a head 13, a shank 14, and a counterbalance 15. The head and shank are integral with each other and the rear of the shank comprises spaced jaws 16 receiving between them a portion of the counterbalance, the shank and counterbalance being pivoted together by pin 17 whereby these two parts of the buffer device may have relative movement transversely of the pilot. A horizontal pin 18 is seated in bearings 19 in the pilot and passes through the end of counterbalance 15 and pivotally mounts the latter and the coupler so they may swing in a vertical plane.

The coupler device may be swung about pivot 18 to a functioning position (shown in Figures 1, 3, 4 and 5) in which coupler head 13 extends forwardly from pin 18 and projects beyond front wall 7 to engage the coupler (not shown) of an adjacent vehicle. In this position counterbalance 15 extends rearwardly from pin 18 with the top

of its rear end abutting a stop 20 projecting downwardly from front end casting 2.

Or the coupler device may be swung upwardly and rearwardly to a retracted position, as indicated in Figure 2, in which the coupler head and shank is moved out of recess R and a web 25 provided on the bottom of the coupler device swings forwardly into the position indicated to close the forward end of recess R and to cooperate with front wall 7 of the pilot to provide a substantially continuous smooth surface from side to side and from top to bottom of the pilot.

The front wall of the pilot has restricted depressions or offset portions at 21 and the sides 15 22 of these depressions provide bearings for a readily removable pin 23 which may be passed through the coupler shank, to hold the coupler device in functioning position, or may be passed through lugs 24 in the coupler device to hold it 20 in retracted position.

The uncoupling rod includes side portions 26 mounted in brackets 27 and extending outwardly to the sides of the car terminating in handle portions 28 for manual operation. The intermediate portion 29 of the uncoupling member must accommodate the upward and rearward movement of the coupler head and shank and this portion is made U-shaped with the ends of its legs pivoted on the inner ends of side portions 30 26, the latter having offsets 30 which, when handles 28 are raised, will positively engage the legs of portion 29 to lift the coupling pin 31 from the coupler head. At the same time the intermediate portion 29 of the uncoupling rod is 35 free to be swung back to the position shown in Figure 2 where it clears the coupler head.

The construction described provides for balanced type of coupler which may be moved readily from operating to retracted position and, 40 when in retracted position, closes the opening in the pilot required for the coupler when in operating position thus improving the appearance and obstacle engaging surface of the pilot by swinging the coupler upwardly instead of downwardly. The recess in the front of the pilot is much smaller than is required in my above mentioned patent and the pilot may be made substantially stronger for a given amount of material. The opening in the front of the pilot 50 is completely closed when the coupler is retracted and only a small amount of the coupler structure is visible.

Obviously many of the details of the structure may be varied without departing from the spirit 55 of the invention and the exclusive use of such modifications as come within the scope of the claims is contemplated.

What is claimed is:

1. In combination, a locomotive pilot having a 60 forwardly and upwardly opening recess, a coupler movably mounted on said pilot and including a head which may be projected forwardly from said recess into position to couple with an adjacent vehicle or may be raised from said position 65 out of said recess, said coupler including a portion spaced from said head and closing the front end of said recess substantially from side to side and from top to bottom when said head is raised.

2. In combination, a locomotive pilot having a 70 front wall with a rounded nose and having a recess in its upper portion, a coupler including a head and a curved web spaced from said head, said coupler being pivotally mounted in said pilot to swing about a horizontal axis from a position, in which said head will project forwardly from

said recess and beyond said wall, to a position in which said head will be located rearwardly of said wall and said web will move forwardly in said recess and continue the surface of said wall across the front of said recess. 5

3. In combination, a locomotive pilot having a front wall provided with a recess, a coupler device pivotally mounted in said pilot and including a head and a counterbalance on opposite sides of its pivot, said coupler device being movable about its pivot from a position in which said head projects forwardly from said recess, to engage the coupler of an adjacent vehicle, to a position above said recess, said coupler device including a web which when said head is raised 10 moves forwardly to close said recess. 15

4. In combination, a locomotive pilot having a front wall with an upwardly and forwardly opening recess, a coupler pivotally mounted in said pilot to swing about a horizontal axis and 20 including a head and a counterbalance on opposite sides of said axis, said coupler being movable from a position in which said head extends forwardly from said axis to a raised position in which said head extends upwardly and 25 rearwardly from said axis, said coupler also including a portion closing the front of said recess and having a wall-like part with its edges lying flush with the adjacent portions of said pilot wall when said head is in the latter-mentioned 30 position.

5. In a railway pilot, a rear wall, a front wall, members extending between said walls, bearing elements in said members for seating a coupler supporting pin, said front wall having a forwardly and upwardly opening recess in front of said bearing elements for receiving and providing for the upward movement of a coupler head rearwardly of the normal front face of the pilot, and said rear wall having a rearwardly and 40 downwardly opening recess at the rear of said bearing elements for receiving and providing for the downward movement of a coupler counterbalance. 35

6. In combination, a locomotive pilot having a front wall, a coupler pivotally mounted on said pilot and movable from a position in which its head projects forwardly from said wall, upwardly and rearwardly to a retracted position where its head is at the rear of said wall, an uncoupling lever rod extending across said pilot and pivotally mounted above said coupler and including a U-shaped portion extending forwardly over said head when the latter is in projected position and extending rearwardly and receiving said head when the latter is in retracted position. 45

7. In combination, a locomotive pilot, a coupler having a horizontal pivot mounting on said pilot and movable from a position in which its head projects forwardly from said mounting beyond said pilot to a retracted position in which its head projects upwardly and rearwardly from said mounting, an uncoupling lever comprising portions pivotally mounted on said pilot 60 at the sides of said coupler, and a central U-shaped portion overlying said coupler with its legs pivotally mounted on the inner ends of said side portions and movable with said head to said retracted position independently of said side 65 portions. 55

8. In combination, a locomotive pilot having a front wall provided with a recess, a coupler device pivotally mounted in said pilot to swing to coupling and uncoupling positions respectively, said 70 75

device including a plate-like member retracted within said recess when said device is moved to coupling position and forming a continuation of the front wall of said pilot and closing said recess when said device is moved to uncoupling position.

5. 9. In combination, a locomotive pilot having a front wall provided with a recess, a coupler device comprising a shank and a head mounted in said pilot to swing about a horizontal axis

to a position with its head projecting forwardly of said wall or to a position in which a portion of said device at the rear of said head closes the opening of said recess and forms a substantially continuous extension of said wall across said opening, said portion being positioned behind said front wall when said head is in projected position.

EINAR G. HALLQUIST.
